UNITED STATES PATENT OFFICE

CORNELIUS MAASHANT, OF SANTIAGO DE CUBA, CUBA

ELECTRIC-LIGHT FIXTURE

Application filed December 31, 1926. Serial No. 158,233.

My invention relates to electric lighting fixtures and particularly to a means for intensifying the light in a desired direction.

In standard types of electric lighting fixtures of the wall-carried or hanging variety, it is necessary that one use relatively high wattage bulbs in order to obtain the requisite downward illumination for reading or other purposes. The reason for this is that an unnecessary amount of light is dispersed ceilingward. The modern trend of interior decoration is toward soft lighting of the walls and ceilings through the medium of low wattage bulbs or ornamental floor or table lamps, either of which are conducive to eye strain when used for reading purposes. With respect to the wall or floor lamps, their artistic effect is spoiled when bulbs of sufficient wattage for reading purposes are applied, and reflectors cannot be used with such lamps without detracting from the appearance thereof.

Briefly summarized, the present day lighting fixtures require excessively high wattage bulbs for reading purposes, the use of which produces glaring ceiling and wall illumination and inartistic effects in floor and table lamps,—all of this being contra to the present day theory of interior decoration which demands soft ceiling and wall illumination. Furthermore, the use of high wattage bulbs is expensive in current consumption.

It is, therefore, the primary object of my invention to overcome the objections noted and to provide means whereby a low wattage bulb may be availed of to preserve the soft toned illumination of ceilings and walls, but which will at the same time produce the bright, concentrated light necessary for reading and kindred purposes.

Another object of the invention is the provision of an appliance which is capable of application to standard types of lighting fixtures without changing the relative positions of the ornamental shades thereof, and without detracting from their attractiveness.

A further and more limited object of the invention is to furnish an appliance for the purpose specified which involves an improved extensible fixture plug having a bulb receiving

extensibility of the plug permitting its reflector to be located in a predetermined position with respect to various kinds of ornamental lamp shades.

The foregoing and other objects of the invention are attained by means of a novel combination and arrangement of parts to be hereinafter described and claimed, and in order that the same may be better understood, reference is had to the accompanying drawings forming a part of this specification. The drawings illustrate what I now regard as a preferred embodiment of the invention but it is to be understood that various changes and modifications may be made therein without a departure from the spirit and scope of the subject matter claimed.

In the drawings, wherein the same reference characters designate the same parts in all views,

Figure 1 is a longitudinal sectional view of the appliance in association with a lamp fixture;

Figure 2 is a sectional view on the line 2—2 of Figure 1 looking in the direction of the arrows;

Figure 3 is a view similar to Figure 2 but looking in the opposite direction;

Figure 4 is a group perspective view of the elements of the extensible plug included in the invention; and

Figure 5 is a perspective view of the reflector supporting element.

Referring specifically to the drawings, and particularly to Figure 1, it is noted that a conventional lamp fixture is shown including a lamp socket 1 carrying a shade S. In carrying out the invention the insulated screw plugged end 2 of the extensible socket member is screwed into the lamp fixture socket 1, the extensible socket member comprehending tubular telescoping sections 3 and 5. The tubular member 3 is secured to the screw plug 2 by an inwardly crimped end flange 3^a engaging the beveled circumferential shoulder 2^a of the plug to thereby hold the plug end against a supporting flange 3^b carried inwardly of the tubular member 3.

The tubular section 5 has opposed tapped bearings 6 receiving screws 7 adapted to ex-

100

tend through closed longitudinal slots 4 in the section or member 3. Thus the sections 3 and 5 of the socket are extensibly connected and may be bound in a predetermined set position by tightening of screws 7.

5 An insulating lining 8 within the extensible socket section 5 separates the porcelain contact carrying base 9 and its associated lamp receiving socket 10 from the wall of socket section 5, it being understood the contact carrying base is frictionally held in place within said section.

10 Figures 1 and 4 clearly show that connection is made between the contact carrying base 9 and its lamp socket 10 by means of a U-shaped stamping 12 screwed to the base as at 15 12^a and engaging inturned flange portions 10^a of the socket 10.

15 The end contact point of the lamp plug 11 20 bears against a center contact piece *c*, secured to the base 9 by a screw *b* which also secures an L-shaped conductor 14 thereto, the latter having an upstanding arm 14^a housed in one of the two side grooves 13 of base member 25 9. The other groove 13 receives the upstanding arm 12^b of the U-shaped stamping 12, as shown. Lamp socket 10 is electrically connected to the plug end 2 of extensible socket section 3 by the flexible wires *W* secured as at 30 15 to elements 14, 14^a and 12, 12^b.

35 The lower end of the extensible plug section 5 is screw threaded as indicated at 5^a to receive the internally threaded annular ring 16 which is formed with diverging arm 17 having at their ends transversely disposed reflector supporting portions 18 of arcual form as best shown in Figure 5.

40 Referring to Figure 1, the reflector 19 is depicted in operative position and supported by the ring arms 17. Inasmuch as arms 17 are divergent, the edges of the central opening 19^a of the reflector are spaced from the lamp bulb 11 and light is permitted to pass upwardly through the space 20 so produced 45 to illuminate the ornamental shade *S* and cast a soft illuminating glow upon the walls and ceiling of the room. The reflector 19 concentrates the major portion of the light rays downwardly and by reason of this a relatively 50 low wattage lamp will furnish just as strong a reading light as would a high wattage lamp without the reflector. Also the objectional brilliant illumination of the walls and ceiling is obviated.

55 It is believed to be obvious from the drawings that the extensibility of the socket 3, 5 enables the reflector to be adjusted to any desired position to suit the particular form of the ornamental lamp shade *S*. With shades of large diameter the reflector 19 may be positioned within the confines of the shade, this being manifest from an inspection of the drawings.

60 The reflector 19 may be made of different

materials and shapes to harmonize with the various kinds of lamp shades.

Having thus described my invention, what I claim as new and desire to secure by Letters Patent is:

70 1. The combination with the bulb receiving socket of a lamp fixture, of an extensible plug having one end inserted in said socket and having a bulb receiving socket at the other end, a reflector carried by said plug and adjustable therewith, a shade supported by and above said reflector and movable therewith, whereby said extensible plug is substantially enclosed by the shade and reflector.

75 2. The combination with the bulb receiving socket of a lamp fixture, of an extensible plug having one end inserted in said socket and having a bulb receiving socket at the other end, a reflector carried by said plug and adjustable therewith, a bell-shaped shade resting on said reflector and enclosing said socket and extensible plug and movable therewith.

80 3. The combination with the bulb receiving socket of a lamp fixture, of an extensible 90 plug having one end inserted in said socket and having a bulb receiving socket at the other end, a reflector having a central opening and being supported by an open support depending from said plug, said open support extending through the reflector, said reflector being adjustable with said plug, a translucent shade supported by and above said reflector and movable therewith, whereby said extensible plug is substantially enclosed by the 95 shade and reflector.

95 4. The combination with a bulb receiving socket of a lamp fixture, of a plug having one end inserted in said socket and having a bulb receiving socket at its other end, said plug being adjustable in the manner to move its receiving socket toward and from its opposite end, a reflector mounted on the socketed end of said plug and adjustable therewith, a shade mounted upon the upper surface of the 100 reflector and movable with the same said shade enclosing said socket and extensible plug.

105 In testimony whereof I affix my signature.

CORNELIUS MAASHANT.
